UNITED STATES PATENT OFFICE

JESSE ROSENBAUM, OF BROOKLYN, NEW YORK

LUGGAGE GUARD

Application filed January 19, 1929. Serial No. 333,730.

This invention relates to safety devices for vehicle carried baggage and more specifically applicable to automobiles provided with platforms on which may be supported small trunks, suit cases, sample cases, etc.

One of the objects of the invention is to provide a hingedly jointed metallic guard suited to engage one or more containers of substantially uniform proportions and retain them upon a support.

Another feature of the invention is to combine with the members of the guard a lock bolt provided with a key operated lock whereby the articles constrained by the guard are held in a manner to resist removal, thus preventing accidental loss or theft.

A further purpose is to produce a series of interengaging elements fixedly secured to the support and also to the articles themselves whereby all are effectively interlocked to constitute a unit.

Other valuable and practical features such as provisions of means for preventing abrasion of the articles held, by cushions on the guard members, in arranging the parts to permit compact folding when not required for use, and in appearance, are attained by the novel construction and combination of few and simple parts as hereinafter described and shown in the accompanying drawing, forming a material part of this disclosure, and in which:

Fig. 1, is a front elevational view of an embodiment of the guard, showing its application.

Fig. 2, is a partial plan view of the support as viewed from under the device.

Fig. 3, is an enlarged fragmentary sectional view taken on line 3-3 of Fig. 2.

Fig. 4, is a view showing the interengaging corner elements of the containers, parts being in section to show the construction.

In the several views a pair of containers, such as trunks, cases or the like, are designated by the numerals 10-10', respectively upper and lower, but it is to be understood that all the several containers usable with one size of the guard are substantially alike in all their proportions.

On each corner of the container are sheet

metal corner pieces 11-11' presenting three plate surface, the side and end plates being flat and plain while the upper and lower adjacent plates are die formed, that of the corner 11 having a circular outstanding projection 12 to engage within the confines of a ring 12' raised from the adjacent face of the corner element 11'.

The guard consists of an upper bar 14 slightly longer than the containers and to extend past their ends as seen in Fig. 1.

Horizontal hinges 15 are disposed at the ends of the bar 14 to connect end bars 16 extensible at right angles as shown, or foldable if desired. Each bar 14 and 16 is provided on its inner surface with cushion buffers 17 to contact the containers when disposed within the guard.

The support plate 18, of greater length than the containers is provided with downwardly bent right angled ends 19 and 20, and also is sheared and bent to produce a plurality of outstanding lugs 21 containing rectangular perforations to receive a locking bolt 22 slidable therethrough.

On one end of the bolt 22 is fixed a perforate bracket 23 receptive of a rod 24 riveted into the plate element 19, the rod being encircled by a coiled compression spring 25 between the element 19 and bracket 23, through which the rod extends and fixed on the free end of the rod are a pair of adjustable stop nuts 26, limiting the movement of the bracket and rod in an outward direction.

Extending downward from the plate 18 are brackets 27 having openings to receive the lower ends of the bar 16 and also transverse openings to permit the offset end 22' of the bolt 22 to pass through, the end also passing through an opening 29 in the lower ends of the bars 16.

The other end of the locking bolt 22 has an offset, re-entrantly turned portion 30 engageable in the corresponding bar 16 and bracket 27 and is further provided with a Z shaped bracket 31 carrying a cylinder lock 32, the same extending through an opening in the front plate element 20 and engageable when adjusted therein to retain the bolt in a locked position.

Obviously, from the foregoing, it will be seen that the longitudinal movements of the locking bolt 22 controls guard bars 16 and 14, locking or unlocking them as may be required.

In order positively to secure the containers within the guard the bottom or support plate 18 is provided with projections 13 to engage the corner rings 12', thus providing positive 10 security as against jolting loose or even unauthorized attempts at removal of the containers, which are accessible only to persons having a key for the lock 32.

Having thus described the invention in the 15 best known embodiment and indicated the scope of its utility and application, what is claimed as new and sought to secure by Letters Patent, is:—

1. A guard for containers comprising a top 20 bar and side bars hinged at the ends thereof, a support plate, a locking bolt slideable on said support plate to secure said guard bars in operative position, a key operated lock for said locking bolt, and means to release said guard bars when said lock is key opened.

2. A guard for containers comprising interengaging corner elements fixed on the containers, a series of bars circumjacent the containers, the top and side bars being hingedly 30 engaged, said top and side bars being removable, a support plate, means to bolt said side bars to said support plate, when in operative position, and inreaching projections on said support plate to engage said corner elements.

3. A guard for containers comprising interengaging corner element fixed on the containers, a support plate, a series of bars circumjacent the containers, the top and side bars being hingedly engaged, cushion buffers 40 on the top and side bars to contact the containers, interengaging means on the support plate to engage said corner elements, and key actuated locking means to secure said side bars in operative position on said support plate.

4. A guard for containers comprising interengaging corner elements fixed on the containers, a support plate for the containers, a series of bars circumjacent the containers, the top and side bars being hingedly engaged, 50 a locking bolt slideable longitudinally on said support plate, means carried by said side bars to engage the ends of said locking bolt, means to positively lock the bolt in operative position, and means on the support plate to prevent removal of the containers when embraced by said bars.

5. Engaging means for containers comprising metal corner elements having projections on one of their contracting surfaces directed 60 upwardly and corresponding recesses on opposed elements directed downwardly to permit registering engagement, a support plate having projections to engage the mentioned recesses, a top bar and end bars hinged to said top bar, means to releasably engage said

bars to said support plate, and means carried by said bars to prevent abrasion of the containers.

6. A luggage guard comprising a support plate, recesses in said support plate, hinged 70 bars to extend over the top and ends of the luggage and through the recesses in the support plate, and means releasably to secure the said bars with the support plate.

7. A luggage guard comprising a support 75 plate, recesses in the said support plate, hingedly connected bars to extend over the top and sides of the luggage and through the said recesses, a sliding multiple headed, spring retracted locking bolt on the under 80 side of said support plate, means on the ends of the bars projecting through the recesses to releasably engage the heads of the locking bolt, and key operated means for locking the bolt in projected position.

Signed at New York, in the county and State of New York, this 26th day of December, 1928.

JESSE ROSENBAUM.
